UNITED STATES PATENT OFFICE.

GEORGE F. MUTH, OF PHILADELPHIA, PENNSYLVANIA, ASSIGNOR TO NEWTON
MACHINE TOOL WORKS, INCORPORATED, OF PHILADELPHIA, PENNSYLVANIA,
A CORPORATION OF PENNSYLVANIA.

INTERLOCKING MECHANISM FOR COLD-SAW-CUTTING-OFF AND LIKE MACHINES.

1,335,597.

Specification of Letters Patent. Patented Mar. 30, 1920.

Application filed January 8, 1919. Serial No. 270,190.

To all whom it may concern:

Be it known that I, GEORGE F. MUTH, a citizen of the United States, residing in Philadelphia, Pennsylvania, have invented 5 certain Improvements in Interlocking Mechanism for Cold-Saw-Cutting-Off and like Machines, of which the following is a specification.

My invention relates to certain improvements in interlocking mechanisms, such as 10 illustrated in the patent granted to M. Meyers, No. 1,081,763, December 16, 1913, in which there is a slow forward feed and a quick return feed. In a machine of this 15 type there are two operating rods and one object of my invention is to provide a simple and effective means whereby an operating lever cannot actuate one rod to move it from its normal position without first moving the 20 other to its normal position.

A further object of the invention is to construct the device so that one operating arm may actuate both rods.

In the accompanying drawings:

25 Figure 1 is a sectional elevation of my improved interlocking device;

Fig. 2 is a plan view;

Fig. 3 is a side view;

30 Fig. 4 is a perspective view of the bearing for the operating rods;

Fig. 5 is a detached perspective view of the operating rods;

Fig. 6 is a perspective view of the operating lever; and

35 Fig. 7 is a face view of the bearing plate.

The machine of the above mentioned patent is a cold saw cutting off machine. In this machine it is desirable to have a slow forward feed while the saw is cutting and a 40 quick return.

1 is a rod, in the present instance, for shifting the operating mechanism, whereby a slow forward feed is thrown into gear. 2 is the rod connected to the mechanism for 45 throwing the quick return feed into gear. In the present instance each rod has a rectangular head. As there is a gear and clutch mechanism, such as illustrated in the above mentioned patent, one rod must be brought to the normal position before the 50 other rod can be operated so that the shifting of the operating rod takes place when both rods are in the normal position, such as in Fig. 3. 3 is a portion of the base of a

cold saw cutting off machine. This base has 55 a bracket 4 carrying a bearing 5 for the rectangular heads 6 and 7 of the rods 1 and 2 respectively. These two rods extend through the base 3 and are connected to the operating mechanism, such as illustrated in the 60 above mentioned patent. The head 6 has a notch 8 and the head 7 has a notch 9. When the two rods are in the normal position, these two notches align with each other, as illustrated in Fig. 5.

10 is a spindle, rectangular in cross section, on which is a hub 11 having an extension 12, which is located in a bearing 13, projecting from a plate 14 secured to the face of the bearing 5. On the lower end of 70 this plate is a bearing 15, which receives the reduced cylindrical end of the spindle 10. The spindle is held from lifting in its bearing by a nut 16 and washer. Screwed into the hub 11, in the present instance, is an operating handle 17. In order to prevent the hub raising off of its bearings 13, I form in the extension 12 an annular groove 18 to receive a pin 19 screwed into the bearing 13 75 so that while the hub can turn on the bearing it cannot be moved longitudinally.

Mounted so as to slide on the square spindle 10 is a sleeve 20 having an arm 21 which extends into the notches in the heads 6 and 7 of the operating rods. The end of this 80 arm 21 is rounded, in the present instance, as at 22, Fig. 6, so as to bear with the least amount of friction on the side walls of the notches and to allow the arm to be shifted from one notch to the other without interference. The arm 21 extends from a slot 23 85 in the plate 14 and this slot has a lateral, elongated extension at its upper end in line with the notch 8 in the head 6 and lateral short extensions 26 and 27 in line with the 90 notch 9 in the head 7. When the lever 21 is in line with the extension 24 of the notch it can only be moved in one direction but when the lever is in line with the notches 26 and 27 it can be moved in either direction. 95

When the sleeve 20 is in the lowest position, it rests upon the bearing 15, but when it is in the raised position, as in Fig. 1, it can be held in this position. In the present instance, I have shown a ball 28, back of 100 which is a spring 29. This ball is adapted to a recess 30 in the spindle 10 and, consequently, when the ball is in this recess the 105

sleeve is held in the upper position and the end of the arm is in the notch 8 of the head 6.

31 is an operating handle screwed into a projection on the sleeve 20 and is the rear bearing for the spring 29.

By the above construction, it will be seen that only one lever is necessary for actuating the two rods. The sleeve on the spindle 10 can be shifted into engagement with the head of the rod 1, or the head of the rod 2, but in order to shift the sleeve the two rods must be in their normal position with the notches 8 and 9 in alinement.

15 I claim:

1. The combination in a shifting device, of two rods, each rod being notched, the notches being so arranged that they will be in alinement when in the mid position; 20 a bearing for the rods; a spindle; a bearing therefor; means for turning the spindle; a sleeve mounted so as to slide on but turn with the spindle; an arm on the spindle extending into the notches; and means for 25 retaining the sleeve in its raised position and in alinement with the upper of the two rods.

2. The combination in a shifting apparatus, of two rods connected to the mechanism to be shifted, each rod having a head; 30 a notch in each head, the two notches being in alinement when the rods are in their normal positions; a locking slot in the plate having lateral extensions in line with the two notches of the heads; an operating rod 35 mounted in the front of the plate; means for turning said rod; a sleeve arranged to slide on but turn with the rod, said sleeve having an arm extending through the slot in the plate and into the notches, the parts being 40 so arranged that when the sleeve is in one of its normal positions, it is in engagement with one head and when it is in the other extreme position, it is in engagement with the other head.

3. The combination in interlocking mechanism, of two rods connected to the means to be actuated; a head on each rod, the two rods being arranged side by side; a notch in each head, said notches being in alinement when the parts are in the normal position; 50 a bearing in which the heads are mounted; a plate located in front of the bearing; bearings carried by the plate; a spindle having a hub mounted in the upper bearing, the spindle having a reduced portion mounted 55 in the lower bearing on the plate; an operating arm secured to the hub; a sleeve arranged to move longitudinally on the spindle but to turn therewith, said sleeve being provided with an arm, the plate having a 60 slot through which the arm extends, the end of the arm being located in the notch in one of the heads, the slot in the plate having a single lateral extension at the upper end and two lateral extensions at the lower end so 65 that the shifting mechanism cannot be turned until it is in either of its two extreme positions and not until the slots in the two heads are in alinement.

4. The combination in interlocking mechanism, of two rods connected to the means to be actuated; a head on each rod; each head having a slot, the two slots being in alinement when the rods are in the normal position; a bearing for the heads; a plate 75 secured to the bearing and having a notch therein, the notch having upper and lower extensions; an operating rod mounted in front of the plate; means for operating the rod; a sleeve mounted longitudinally on the 80 rod, but arranged to turn therewith; and a spring-pressed ball carried by the sleeve and adapted to the notch in the spindle so that the sleeve will be held in its upper position by the ball.

In witness whereof I affix my signature.

GEORGE F. MUTH.
